UNITED STATES PATENT OFFICE.

CHARLES STINSON, OF ST. THOMAS, ONTARIO, CANADA.

BANK DESK.

Application filed July 31, 1922. Serial No. 572,809.

To all whom it may concern:

Be it known that I, CHARLES STINSON, a subject of the King of Great Britain, and resident of the city of St. Thomas, in the county of Elgin and Province of Ontario, Canada, have invented certain new and useful Improvements in Bank Desks, of which the following is a specification.

My invention relates to improvements in desks and tills for cashiers and tellers in banks, or for use in other places where money or valuables are handled which are apt to be the object of theft.

One object of the invention is to provide a desk or till that can be caused to disappear from view by passing through the floor, and will be thus rendered inaccessible from the room in which is ordinarily is placed.

A further object is to provide a device of this character that will be simple in construction and rapid and efficient in operation, and wherein, after a slight initial operation, the whole device is automatic in character.

These and other objects will be apparent from the following description and the appended claims.

In the drawings:

Figure 1 is a perspective view of the desk as it appears in use;

Figure 2 is a perspective view with parts in section, of the entire device;

Figure 3 is a vertical section thereof;

Figure 4 is a section on the line 4—4 of Figure 3, looking in the direction of the arrows at the ends of said lines.

Figures 5 and 6 are vertical sections on the lines 5—5 and 6—6 respectively of Figure 4, looking in the direction of the arrows at the ends of said lines.

The device consists of two main parts, an upper, inner or desk section 1 located mainly above the floor when in use, and a lower, outer or receiving section 2, located beneath the floor.

Attached to a bracket 3 or other suitable support in the part 1 is a vertical rack member 4 which meshes with a pinion 5 carried by a shaft 6 mounted at its inner end in a standard 7 carried by the section 2 and at its outer end has a bearing 8 in the wall of the section 2. A key or crank 9 adapted to fit the end of the shaft 6 is used for rotating the same when it is desired to move the section 1 into upper position.

The section 1 is normally held in its upper or operative position by pins 10 that pass through the walls of the sections 1 and 2 and through spacing blocks 11 therebetween. At their outer ends these pins are pivoted to arms 12 fastened to shafts 13 mounted in bearings 14. The front end of each shaft 13 carries a bevel gear 15 and these bevel gears mesh with bevel gears 16 on a shaft 17 mounted in bearings 17' at the front of the device. All of the bearings 14 and 17', as well as the shafts and gears, are preferably mounted beneath the floor and are carried by the section 2. The shaft 17 has attached thereto an arm 18 which is engaged by a pin 19 passing through the floor A. This pin is normally held in raised position by a coiled spring 20 and has a button or knob 21 at its upper end.

Pivoted at 22 to the inner side of the section 2 is a member 23 having a tongue 24. There are preferably four of these members as illustrated. To the opposing outer sides of the section 1 are attached blocks 25 with grooves 26 adapted to receive the tongues 24 when the section 1 is lowered into the section 2. The manner in which these parts engage is clearly shown in Figure 4. Each member 23 is normally pressed inward at its lower end by a compression spring 27 mounted in a housing 28 and having a screw 29 for adjusting its tension.

Mounted to slide in the section 1 is a drawer or till 30 having a handle or knob 31 on its front end and a ratchet member 32 attached to its under side. A spring 32' has one end attached to the till 30 and its other end to a shaft 33 mounted in a bracket arm 34 extending from the side of the section 1. Pawl and ratchet mechanism 35 keeps the spring under any desired tension.

To retain the till 30 open against the tension of the spring 32' there is provided a detent 36 (Figure 6) pivoted to a side of the section 1 at 37 and connected by a link 38 to a lever 39 pivoted at 40 and having a finger piece 41 extending through a slot 42 in the front wall of the casing 1. Branching from the link 38 is an arm 43 upon which is a pin 44 in position to engage a spring arm 45 fastened to the section 2 when the section 1 is lowered. The detent 36 is normally held in engagement with the ratchet 32 by a spring 36'.

When the section 1 is lowered a contact 47 thereon engages two contacts 48 on section 2 to close a circuit. This may operate a bell or any desired signal.

- 5 The shaft 17 is provided with a spring 49 to normally hold the pins 10 in locking position, and to return them to such position when the section 1 is raised after having been previously lowered.
- 10 The operation of the device is evident from what has been said, but may be briefly summarized as follows: Supposing the parts to be in the normal working position shown in the figures. The till 30 is held open by 15 the detent 36 engaging the ratchet 32, and if it is desired to close the same, the finger piece 41 is moved to the opposite end of the slot 42 thus moving the detent out of engagement with the ratchet and permitting 20 the spring 32' to retract the till 30 to the position shown in Figure 2.

If the till is open and it is desired to cause the whole device to disappear, the operator steps upon the button 21. This rotates the shafts 17 and 13, withdrawing the locking pins 10 from the section 1 and permitting it to drop by its own weight. In this downward movement the engagement of the members 25 with the cooperating spring 30 pressed members 23 serve to guide the section 1 and acts as a buffer to prevent too sudden a fall and resulting shock.

As soon as the section 1 begins its descent, the engagement of the pin 44 with 35 the member 45 rocks the detent 36 out of engagement with the ratchet 32 through the connections 43 and 38, and thus permits the spring 32' to draw the till to closed position before it reaches the level of the floor, thus 40 preventing the till from being caught on the floor.

When it is desired to return the parts to normal position, the shaft 6 is rotated by means of the key or crank 9 and the resultant rotation of the pinion 5 moves the rack 4 and section 1 to operative position. As soon as normal position is reached, the spring 49 rotates the shafts 17 and 13, thus moving the pins 10 into locking position.

50 The device may be made of any desired material. If the size renders it advisable, the rack 4 and pinion 5 may be duplicated. It is obvious that by any suitable extension, the shaft 17 may be operated from a distance to trip the mechanism.

While illustrated as a bank desk provided with a till, it is obvious that the invention may be used in other relations and without said till. Manually operated means for 60 raising the section 1 to operative position have been shown, but power means for rotating the shaft 6 may be employed without departing from the scope of the invention.

I claim:

- 65 1. In a bank desk, an upper or desk sec-

tion, a lower section into which the upper section may telescope, means for holding said upper section in operative position, a sliding drawer in the upper section, means tending to hold said drawer closed, detent mechanism for locking the drawer open, means for releasing the holding means and permitting the upper section to drop, and means operated by the movement of the upper section for releasing the detent mechanism and permitting the drawer to close.

2. In a bank desk, an upper or desk section, a lower section into which the upper section may telescope, means for holding the upper section in operative position, a sliding drawer in the upper section, spring means tending to hold said drawer closed, a ratchet carried by said drawer, detent means engaging the ratchet to lock the drawer in desired open position, manual means for releasing the detent mechanism, means for releasing the holding means and permitting the upper section to drop, and means operated by the telescoping movement of the upper section for releasing the detent mechanism and permitting the drawer to close.

3. In a bank desk, an upper or desk section, a lower section into which the upper section may telescope, means for holding the upper section in operative position, a sliding drawer in the upper section, means for locking said drawer open, means for releasing said holding means and permitting the upper section to drop and automatic means for releasing and closing said drawer upon the movement of the upper section.

4. In a bank desk, a desk section adapted to move from operative to inoperative position, means for holding the desk section in operative position, a sliding drawer therein, means for retaining the drawer open, and automatic means controlled by the movement of the desk section to inoperative position for closing said drawer.

5. In a bank desk, a desk section adapted to move from operative to inoperative position, means for holding the desk section in operative position, a movable compartment therein, means for retaining said compartment open, and automatic means controlled by the movement of the desk section to inoperative position for closing said compartment.

6. In a bank desk, an upper or desk section, a lower section into which the upper section may telescope, means for holding the upper section in operative position, said means comprising pins passing through the walls of both sections, shafts to which said pins are connected, and means for rotating all of said shafts to simultaneously withdraw said pins and permit the upper section to drop to inoperative position.

7. In a bank desk, an upper or desk sec-

tion, a lower section into which the upper section may telescope, means for holding the upper section in operative position, grooved members carried by the upper section and 5 spring pressed tongued members carried by the lower section, said members being adapted to engage during the telescoping movement of the upper section to guide said section and act as a buffer therefor.

10 8. In a bank desk, an upper or desk section, a lower section into which the upper section may telescope, grooved members carried by the upper section, a plurality of members carried by the lower section, each 15 member being pivoted at one end to a wall and spring pressed away from the wall at its other end and provided with a tongue, the tongue and groove members engaging during the telescoping movement of the upper 20 section, thereby acting as guides during the movement and as a buffer therefor.

9. In a bank desk, an upper or desk section, a lower section into which the upper section may telescope, grooved members carried by one section, tongued members carried by the other section, each tongued member being pivoted at one end to a wall, a spring to engage the other end thereof, and means for varying the tension of the spring, said 25 30 spring members acting as a buffer during the telescoping movement of the upper section.

10. A bank desk comprising two sections

normally in extended operative position but adapted to collapse, means for holding the sections in operative position, means for releasing said means and permitting the sections to collapse, and a buffer comprising a member pivoted near one end to the outer section and spring pressed into position to be engaged by the inner section in its descent to absorb the jar of the collapsing movement.

11. A bank desk comprising an upper or desk section, a lower section into which the upper section may collapse, a rack member 45 carried by the upper section, a pinion engaging said rack, a shaft mounted in the lower section and carrying said pinion, and means for rotating said shaft to move the upper section to extended position.

12. A bank desk comprising an upper or desk section, a lower section into which the upper section may collapse, a rack member carried by the upper section, a pinion engaging said rack, a shaft mounted in the 55 lower section and carrying said pinion, means for rotating said shaft to move the upper section to extended position, and means automatically operative when the upper section reaches its extended position for 60 locking the sections in said position.

In testimony whereof, I have hereunto subscribed my name.

CHARLES STINSON.
